STRINGED INSTRUMENT

Clarence Biederman, Lima, Ohio

Application April 28, 1942, Serial No. 440,836

3 Claims. (Cl. 84—312)

The present invention relates to improvements in stringed musical instruments and more particularly to means for varying the tension of the strings thereof.

An object of the invention is to provide a string tension varying device of generally improved design.

Another object of the invention is to provide a device of the aforesaid character wherein the tension of one or more strings may be varied upon movement of a single operating element.

A further object of the invention is the provision of a device of the above character which is relatively simple in construction and which may be quickly and easily operated.

Other objects and advantages of the invention will become apparent as the description progresses.

In the accompanying drawing forming a part of this specification and in which like numerals are employed to designate corresponding parts throughout:

Figure 1 is a fragmentary plan view of a stringed instrument showing the invention applied thereto.

Figure 2 is a side elevational view of the same.

Figure 3 is an enlarged section taken on line 3—3 of Figure 1 with the operating handle in raised position.

Figure 4 is a transverse sectional view taken on line 4—4 of Figure 3.

Figure 5 is a section taken on line 5—5 of Figure 3, and

Figure 6 is a section viewed from line 6—6 of Figure 3 with the cover in separated relation.

Referring in detail to the drawing, wherein for the purpose of illustration is shown a preferred example of the invention, 10 generally designates a stringed instrument, in the present example an electric Hawaiian guitar, having strings 11, 12, 13, 14, 15 and 16 extended to the rear end of the body or sound box.

To the rear end of this instrument 10 is fastened a channel-shaped support bracket 17 which may be formed of sheet metal providing a pair of complementary elongated side plates 18 arranged vertically of the instrument and projecting above the top of the sound box. Between the plates 18 is provided a vertical web portion 19 having top and bottom portions bent inwardly to form flanges 20 and 21 disposed against the top and bottom of the instrument, as shown to advantage at Figure 4. The web portion 19 and the bottom flange 21 may be firmly secured to the instrument body by screws

22 while the upper angular portion of the web is preferably shaped to form an outwardly protruding transverse lip 23. Adjacent the top edge of each side plate 18 is provided a transverse slot 24 opening into the outer edge while the bottom portion is cut out to provide an angular recess 25.

Journaled on and extending transversely between the side plates 18 is a rotary member 26 in the form of a cylindrical elongated barrel formed at the ends with reduced journals 27 adapted to be rotatably extended through the bearing slots 24. The barrel 26 is shaped to provide, at axially spaced intervals, a plurality of circumferential grooves 28 extending partially about the barrel to form cam portions or sections having arcuate segments of an exterior radius corresponding to the radius of the barrel and segments of reduced radius, shown to advantage at Figure 6, the profiles of these cam sections varying as to the extent of the reduced grooved portions and as to the circumferential arrangement thereof, as best shown at Figure 3.

Supported on and extending between the side plates 18 below and inwardly of the barrel 26 is a shaft 29 parallel with the barrel and of smaller diameter. This shaft 29 supports thereon a plurality of rocker elements 30 of L-shaped formation having right angular arms and provided with transverse bores 31 at the juncture of the arms for rocker mounting on the shaft 29. These rocker arms are spaced on the shaft by means of sleeves and spacing collars 32 and 33 respectively, to assume predetermined coacting positions with relation to the grooved cam sections of the barrel. In the embodiment shown, a plurality of rockers 30 are formed so that the right angular arms are of approximately uniform width. One of the rocker elements indicated at 34 is shaped so that one arm thereof is enlarged to form a lateral extension 35. The upper end portions of the upstanding arms of the rocker elements are formed with apertures 36 designed for connection therewith of one end of certain strings of the musical instrument. The opposite, approximately horizontal, arm of each of the rocker elements 30 is formed with an interiorly threaded aperture 37 adapted to receive therein a screw 38 which is adjustable transversely of the arm and which may be secured in adjusted position by a nut 39. The rocker element 34 carries two of the adjustable screws 37 in spaced relation, as illustrated at Figure 3.

To the protruding end of each of the journals 27 is secured the inner end of a radially

disposed arm 39, these arms being disposed for connection with the ends of a transverse bar 40 forming an approximately U-shaped handle for turning the barrel.

On the support member 17 is normally positioned a cover 41 embodying a pair of end plates 42, corresponding to the end plates 18, connected by a top wall 43 and an outer wall 44. In the upper portions of the plates 42 are provided slots 45 adapted to be slidably fitted over the journals 27 when the cover is in closure position, as shown in Figures 3 and 4. The cover is removably fastened on the holder bracket by means of screws 46 engageable with registering apertures 47 in these elements.

In the example illustrated, the instrument 10 is equipped with six strings, the string 11 of which has its rear end or terminal secured in fixed position to the instrument, as shown to advantage at Figure 1, while the remaining five strings are extended rearwardly for connection with the respective rocker elements 30 and 34. The inner or upper ends of the adjusting screws 37 on the rocker elements project from the arms for engagement with the cam sections of the barrel so that upon arrangement of the barrel in varying angular positions the screws 37 will assume registration with the protruding or the recessed grooved portions of the cams. In the arrangement shown, when the operating handle 40 is in uppermost position with the arms 39 thereof disposed vertically, five of the cams will be disposed so that their portions of greatest radius will contact with the screws 37 of the rocker elements to dispose said elements in such arrangement that the strings 12 to 16 inclusive, will be under greatest tension. If the barrel is rotated in a clockwise direction through an arc of ninety degrees it will attain a position, with the handle extending rearwardly, as shown at Figures 1 and 2, wherein the inner ends of the screws 37 can enter the grooves 28 under the tension of the strings and thereby decrease or slacken the tension and change the pitch of the strings. When the rockers are thus related to the barrel the upstanding arms thereof may be disposed to bear against the lip 23 of the holder. When the handle is swung to a third position, downwardly with relation to the holder, as shown in dotted lines at Figures 2 and 4, the screws of certain of the rockers will remain in the grooves so that certain of the strings such as the strings 13 to 16 remain slackened. Due to the arrangement of the barrel groove in coacting relation with the adjusting screw in the offset portion 35 of rocker 34, however, the screw of this rocker will be depressed by the cam so as to restore the string 12 to a condition of increased tension.

In each of the respective tuning positions of the cam member or barrel, which are attained by selective movement of the handle, a plurality of strings of the instrument are tensioned to effect a predetermined tuning or chord. In addition to various tuning combinations obtainable upon angular adjustment of each barrel, further tuning combinations can be made available by interchanging barrels on the holder bracket. It

will also be apparent that the invention is applicable to stringed instruments of various forms and having a varying number of strings.

It is to be understood that the form of my invention herewith shown and described is to be taken as a preferred example of the same and that various changes relative to the material, size, shape and arrangement of parts may be resorted to without departing from the spirit of the invention or the scope of the subjoined claims.

Having thus described my invention, I claim:

1. In a tensioning device for a musical instrument having a plurality of strings, a support adapted for attachment to the instrument, a plurality of angular rocker elements pivotally mounted on the support to rock in the direction of the strings, a projection carried by each rocker element, means at one end of each rocker for engaging a string, a barrel pivotally mounted on the support parallel with the pivot axes of the said rocker elements, the said barrel having a plurality of circumferential cam forming sections against which the projections of the respective rocker elements are held by the tension of the strings, and means attached to the barrel for turning the same to vary the tension of the strings.

2. In a tensioning device for a musical instrument having a plurality of strings, a support adapted for attachment to the instrument, a plurality of angular rocker elements pivotally mounted on the support so as to rock in the direction of the strings, an adjustable projection carried by each of the rocker elements, each of the said rockers having one end adapted for engagement with a string, a barrel pivotally mounted on the support parallel with the axes of the said rockers, the said barrel having a plurality of circumferential arcuate grooves at longitudinally spaced intervals coacting with corresponding arcuate portions of the barrel surface to provide cam sections against which the projections of the respective rocker elements are pressed by the tension of the strings, and means attached to the barrel for selectively turning the same to vary the tension of the strings.

3. In a tensioning device for a musical instrument having a plurality of strings, a support adapted for attachment to the instrument, a plurality of angular rocker elements pivotally mounted on the support so as to rock in the direction of the strings, an adjustable projection carried by each of the rocker elements, each of the said rockers having one end adapted for engagement with a string, a barrel pivotally mounted on the support parallel with the axes of the said rockers, the said barrel having a plurality of circumferential arcuate grooves at longitudinally spaced intervals coacting with corresponding arcuate portions of the barrel surface to provide cam sections against which the projections of the respective rocker elements are pressed by the tension of the strings, and a U-shaped handle having connection with the ends of the barrel for selectively turning the latter to vary the tension of the strings.

CLARENCE BIEDERMAN.
